DESIGN FOR A TABLE TOP EXTENSION

William D. Craig, Webster Groves, Mo.

Application April 20, 1946, Serial No. 128,814

Term of patent 14 years

(Cl. D33—14)

To all whom it may concern:

Be it known that I, William D. Craig, a citizen of the United States, residing at Webster Groves, in the county of St. Louis, State of Missouri, have invented a new, original, and ornamental Design for a Table Top Extension, of which the following is a specification, reference being had to the accompanying drawing, forming part thereof.

I claim:

The ornamental design for a table top extension, substantially as shown.

WILLIAM D. CRAIG.
